[57] **CLAIM**

The ornamental design for a license plate frame, as
shown and described.

DESCRIPTION

FIG. 1 is a top plan view of a license plate frame showing
my new design;

FIG. 2 is a front elevational view thereof;

FIG. 3 is a bottom plan view thereof;

FIG. 4 is a right side elevational view thereof;

FIG. 5 is a left side elevational view thereof;

FIG. 6 is a rear elevational view thereof;

FIG. 7 is a top plan view of another embodiment of a
license plate frame of the design, the bottom plan view
being the same;

FIG. 8 is a front elevational view of FIG. 7;

FIG. 9 is a right side elevational view of FIG. 7, the left
side elevational view being the same; and,

FIG. 10 is a rear elevational view of FIG. 7.
